United States Patent Office.

STEPHEN R. ROSCOE, OF OBION COUNTY, TENNESSEE.

Letters Patent No. 64,799, dated May 14, 1867.

IMPROVED SOFA BEDSTEAD.

The Schedule referred to in these Letters Patent and making part of the same.

TO ALL WHOM IT MAY CONCERN:

Be it known that I, STEPHEN R. Roscoe, of Obion county, and State of Tennessee, have invented a new and improved Sofa or Settee Bedstead; and I do hereby declare that the following is a full and exact description thereof, reference being had to the accompanying drawings and letters of reference and figures marked thereon.

The nature of my invention consists in providing a double-seated spring or other sofa, and when the upper seat is turned back it revolves in its own frame, so as to furnish the spring or cushion surface for a bed.

To enable others skilled in the art to make and use my invention, I will proceed to describe its construction and operation.

I construct my sofa or settee with two separate, distinct, and complete seats, and these may be plain spring or cushioned, A B. These two seats are united by hinges *a a*. The seat B is made stationary, while the seat A is so constructed as to revolve on pivots at each end, and to move easily within its own frame *b b*. When the frame *b b* is raised and turned back, the seat A would necessarily be upside down, but by releasing or drawing back the pins or bolts *c c*, this seat will revolve upon its pivots and reverse its position, again presenting the cushioned or spring surface for use as a bed. While being thus used as a bed, the projections *c c* come in contact with the floor, and form the necessary feet for the bedstead. When the sofa or settee is opened for use as a bedstead, the rear slats or pieces composing the frames *b b* and *f f* are caused to slide under the seat B, so as not to interfere with the position of the cushions for sleeping purposes, sliding through grooves cut in the lower portion of the posts *g g*. When seat A is replaced on seat B, as a sofa, lounge, or settee, these sliding pieces are held firmly in their places by braces of leather or other suitable material extending from the bottom of the sofa or lounge to the lower and upper inside surfaces of the sliding pieces.

What I claim as my invention, and desire to secure by Letters Patent, is—

The revolving lower cushion or seat of the sofa, secured in its position as described, in combination with the movable portion of the frame, passing out of the way and beneath the cushions or seats, as herein substantially described.

STEPHEN R. ROSCOE.
